SHOE SOLE AND HEEL COLORING DEVICE

Loyal Nancarrow, Royal Oak, Mich.

Application October 28, 1936, Serial No. 108,021

4 Claims. (Cl. 15—166)

My invention relates to improvements in shoe sole and heel coloring devices.

One of the objects of my invention is to provide a novel device of the kind described with which coloring matter, such as black or tan polish may be easily and quickly applied to the sides and back of the heel and to the edges and exposed upper edge portions of the sole of a shoe, without liability of the coloring material discoloring or smearing the upper portion of the shoe or boot.

Another object of my invention is the provision of novel guarding means on a brush or dauber, adapted for applying coloring material to a shoe sole, which can be readily moved from an operative guarding position to one which will permit of the insertion of the bristles of the brush or dauber into the coloring material without contacting the guarding means with such material.

Still another object of my invention is the provision of a novel device of the kind described which permits easy access of the bristles of the brush to the concave edge portions of the sole.

A further object of my invention is the provision of novel means for releasably reliably holding the guarding means in its operative position.

Another object of my invention is the provision of a device of the kind described, which is simple, cheap to make, strong, durable, not likely to get out of order, and which is efficient in its operation.

The novel features of my invention are herein-after fully described and claimed.

In the accompanying drawing, which illustrates preferred forms of my invention,

Fig. 1 is a side elevation, partly broken away, of one form of my invention, in which the wider flange projects outwardly beyond the outer ends of the bristles, the guard member being shown in its operative position on the brush, and pivoted to the brush.

Fig. 2 is a view similar to Fig. 1, showing the guard member swung from its operative position.

Fig. 3 is an inside view of the guard member of Fig. 1, detached.

Fig. 4 is an enlarged section on the line 4—4 of Fig. 1.

Fig. 5 is a side elevation, partly broken away, of another form of my invention, which is similar to that shown in Fig. 1, excepting that the bristles extend outwardly to substantially the outer edge of the wider guard flange, the guard member being shown in its operative locked position.

Fig. 6 is an enlarged section on the line 6—6 of Fig. 5.

Fig. 7 is a side elevation, partly broken away,

of another form of my invention in which the guard member is longitudinally slidable on the brush to and from the operative position, and in which the wider guard flange projects outwardly beyond the bristles, the guard member being shown in its operative position.

Fig. 8 is a side elevation of the structure shown in Fig. 7, with the guard member shown slid from its operative position.

Fig. 9 is an inside view of the guard member 10 of Fig. 7, detached.

Fig. 10 is an enlarged section on the line 10—10 of Fig. 7.

Fig. 11 is a view similar to Fig. 1, of another form of my invention, similar to that shown in Fig. 7, excepting that the bristles extend substantially even with the outer edge of the wider guard flange.

Fig. 12 is an enlarged section on the line 12—12 of Fig. 11.

Similar characters of reference designate similar parts in the different views.

In each of the forms of my invention shown in the drawing, the brush has the usual back 1 having a handle 2, and bristles 3 extending from one side of the back, the outer ends of the bristles forming a longitudinal convex arc, whereby the bristles may be easily applied to concave edge portions of the sole of a shoe or boot.

In the form shown in Figs. 1 to 4 inclusive, there is provided a guard member the body 4 of which is, preferably, of sheet metal, having at one end two projecting flanges 5 which are disposed at opposite sides of the handle 2 to which they are pivoted by a transverse pin 6. This pivotal connection enables the body 4 to be swung from its operative position flatwise against the rear side of the back 1, whereby the bristle end of the brush may be dipped into coloring material, such as black or tan polish, without dipping therein the 40 guard member.

The other end of the guard body 4 has extending from it at its opposite edges respectively two longitudinal flanges 7 and 8, which in the operative position, shown in Figs. 1 and 4 are respectively at opposite sides of the back 1.

The flange 7, in the operative position, extends outwardly a short distance from the outer ends of the bristles 3, and its outer edge is convexly arcuate and substantially parallel with the arc 50 of the outer ends of the bristles 3. The bristles 3 extend outwardly beyond the outer edge of the flange 8.

For releasably holding the guard member in its operative position, the body 4 between the flanges 55

7 and 8 has through it a longitudinal slot 9 through which is adapted to extend a locking member 10 comprising, as shown, a screw 11 revolvably fitted in the back 1 and having at its outer end an eye 12.

5 When the screw eye 12 is turned to the longitudinal position shown in Fig. 2, it can pass through the slot 9, thereby permitting the guard to swing to and from the operative position, shown in Fig. 1. After the guard is swung into the position shown in Fig. 1, and the screw eye 12 is turned to the transverse position, shown in Fig. 1, the screw eye will hold the guard member in the operative position, thereby relieving the 15 operator of this duty.

In the use of the forms shown in Figs. 1 to 6, the screw eye 12 is turned to the release position, shown in Fig. 2, and the brush has its bristle end inserted into the coloring material. The 20 guard member 4 is then swung to the operative position, shown in Figs. 1, 4, 5 and 6, and the brush is employed to apply the coloring material which is on the bristles 3, to the edge and upper exposed edge portion of the shoe sole, the arcuate outer portions of the bristles 3 and the flange 7 permitting the application of the coloring material easily to the concave edge portions of the sole. The flange 7, during such application, and during the application of the coloring material 25 to the upper side of the exposed edge portion of the sole, being disposed next to the shoe upper portion, thus prevents the coloring material which is on the bristles 3 from contacting with and smearing such upper portion.

30 35 By having the bristles 3 extending outwardly a substantial distance from the outer edge of the flange 8, the coloring material can be quickly and easily applied to the sides and back of the heel of the shoe, by tipping the brush downwardly laterally and brushing downwardly with the bristles.

The forms shown in Figs. 1 and 5 differ only in the length of the bristles 3 with respect to the width of the wider flange 7, the bristles in the 45 form shown in Fig. 1 being slightly at the inner side of the arcuate edge of the flange 7, while in the form shown in Fig. 5, the bristles 3 extend substantially to the arcuate edge of the flange 7. The mode of operation of the two forms is the 50 same.

In the forms shown in Figs. 7 to 12 inclusive, the guard member comprises a sheet metal body 13, corresponding in function to the body 4 of Fig. 1, and which is longitudinally slidable on the 55 rear side of the back 1 of the brush and is provided with a longitudinal slot 14 through which extends a screw 15 which is revolvably fitted in the handle 2 of the brush. The screw 15 has an eye 16, which holds the body 13 to the back and also limits its longitudinal range of movement. By turning the screw eye in the proper direction, it may be made to hold the body 13 from longitudinal accidental movement.

65 One end of the body 13 is provided at one side with two oppositely disposed flanges 17 which embrace opposite sides of the brush handle 2, and which serve as finger holds for longitudinally sliding the body 13 to and from its operative position. The other end portion of the body 13 is provided at its longitudinal edges with two oppositely disposed flanges 18 and 19, respectively corresponding in function to the flanges 7 and 8 of the form shown in Fig. 1. In both forms, shown 70 in Figs. 7 and 11, the bristles 3 project outwardly

beyond the outer longitudinal edge of the flange 19.

In the form shown in Figs. 7 to 10 inclusive, the flange 18 extends outwardly slightly beyond the outer ends of the bristles 3 and has its longitudinal outer edge convexly curved substantially parallel to the curve of the outer ends of the bristles 3. In the form shown in Figs. 11 and 12, the bristles 3 extend outwardly substantially even with the outer curved edge of the flange 18. In 10 all other respects, the forms shown in Figs. 7 to 12 are alike.

The flanges 18 and 19 are both longitudinally inwardly creased at 20 so as to slidably engage the bristle side of the body 13 to hold that end 15 portion of the guard from rearward movement away from the back 1.

In the operation of the forms shown in Figs. 7 to 12, the guard member is slid on the brush back to the position shown in Fig. 8 in which the 20 guard will clear the bristle end of the brush, thus permitting such end to be inserted into the coloring material without having the latter get onto the guard.

25 After dipping the brush, the guard member is slid to its operative position, shown in Figs. 7 and 11, following which the operation of applying the coloring material to the sole and heel of a shoe corresponds to that described with reference to the other forms of the invention. 30

To prevent the coloring material getting onto the outer side of the body 13 and flanges 18 and 19, when the guard member is slid to its operative position, after dipping the brush, the outer ends of the flanges 18 and 19 and body 13 are 35 outwardly flared as indicated at 21. This flaring of the parts permits the coloring material to enter between the flanges 18 and 19, as the guard member is slipped to its operative position.

The guard member may be removed from the 40 brush as follows:—turn the screw eye 16 to a position parallel with the slot 14, bend the end portion of the body 13 having the flanges 17 rearwardly from the brush handle 2 to a position such that the body 13 will clear the outer end of 45 the eye 16, and then slide the guard member off from the outer or bristle end of the brush back 1.

The guard member may be replaced on the brush by reversing the operation just described.

Other modifications, within the scope of the 50 appended claims, may be made without departing from the spirit of my invention.

What I claim is:—

1. In a device of the kind described, the combination with a brush having a back and bristles 55 extending from one side thereof, of a member engaging said back and having a slot and a flange and movable to and from an operative position in which said flange will extend from said back at one side of and adjacent to the outer ends of 60 said bristles, and a locking member mounted on said back and adapted to be extended through said slot and movable in said slot to two positions in one of which it will engage and hold said first named member against said back, and when in 65 the other position being adapted to pass through said slot and release said first named member.

2. In a device of the kind described, the combination with a brush having a back and bristles 70 extending from one side thereof, of a member pivoted to said back and having a slot and a flange and adapted to be swung to and from an operative position in which said flange will extend from said back at one side of and adjacent to the outer ends of said bristles, and a locking member 75

mounted on said back and adapted to be extended through said slot and movable in said slot to two positions in one of which it will engage and hold said first named member against said back in said operative position, and when in the other position being adapted to pass through said slot and permit said first named member to be swung from said operative position.

5. 3. In a device of the kind described, the combination with a brush having a back and bristles extending from one side thereof, of a member engaging said back and having a longitudinal slot and a flange and adapted to be slid longitudinally to and from an operative position in which 10 said flange will extend from said back at one side of and adjacent to the outer ends of said bristles, and a locking member mounted on said back and adapted to be extended through said slot and movable in said slot to two positions in one of 15 which it will engage and hold said first named member against said back and when in the other

position being adapted to pass through said slot and permit said first named member to be moved from said back.

4. In a device of the kind described, the combination with a brush having a back and bristles extending from one side at one end portion thereof, of a member longitudinally slidably engaging said back and having a U-shaped channel portion open at its ends and one side and having its two longitudinal flanges of different widths 10 and oppositely disposed at opposite sides respectively of said back, said member being slidable lengthwise on and supported by said back, from an operative position in which said bristles will extend outwardly beyond the outer edge of one 15 of said flanges and the other flange will extend outwardly to the outer ends of said bristles to a position in which said member will be withdrawn apart from and clear of said one end portion and the bristles thereon.
